UNITED STATES PATENT OFFICE.

GEORGE F. HOPKINS, OF NEW YORK, N. Y., ASSIGNOR TO POLLARD-ALLING MANUFACTURING COMPANY, A CORPORATION OF NEW YORK.

PRINTING-MACHINE.

No. 866,863.

Specification of Letters Patent.

Patented Sept. 24, 1907.

Application filed March 18, 1902. Serial No. 93,763.

To all whom it may concern:

Be it known that I, GEORGE F. HOPKINS, a citizen of the United States, residing in the city, county, and State of New York, have invented certain new and 5 useful Improvements in Printing-Machines, of which the following is a full, clear, and exact description.

My invention relates to printing machines which are particularly adapted for addressing envelopes, postal cards, wrappers and the like, but which may obviously 10 be used for a variety of purposes.

The object of my invention is to provide a simple and efficient device of the character specified, and to these and other ends which will hereinafter appear, my invention consists of the novel construction, arrangement and combination of parts to be hereinafter described and particularly pointed out in the appended claims.

In the accompanying drawings wherein like reference characters indicate corresponding parts in the various 20 views—Figure 1 is a front elevation of one form of printing machine embodying my invention. Fig. 2 is an enlarged detailed fragmentary elevation with parts broken away of the machine; the view being taken from the opposite side of the machine from that illustrated in Fig. 1. Fig. 3 is an enlarged elevation, partly 25 in section of the movable bed-plate or support for the paper or article to be printed and the means for actuating it. Fig. 4 is a detailed side elevation of the ink font and inking mechanism. Fig. 5 is an enlarged 30 fragmentary detail view of a portion of the bed-plate actuating means. Fig. 6 is a transverse sectional view through a portion of the machine. The view illustrating the means employed for throwing the locking pawl out of operation. Fig. 7 is a detail perspective view 35 of a chain of assembled printing plates; the view illustrating the printing surface of said plates. Fig. 8 is a like view of the same, taken from the opposite side of the printing plates. Fig. 9 is a detailed edge view 40 of the same; the view illustrating the relative positions of the plates assume in the machine. Fig. 10 is an edge view of the printing plates; the view illustrating the manner in which the plates are turned relatively one 45 to another in order to separate them.

In the various views parts have been omitted and 50 broken away in order to more clearly illustrate other features of the machine.

Generally speaking the machine comprises an impact drum or impression cylinder which is adapted to feed a chain of printing plates and to receive the impact of the material to be printed as it is forced by the 55 movable bed plate or carrier against the printing plates and after they have been properly inked in their approach to the printing point.

In the drawings 1 designates the fixed bed-plate of

the machine frame which may be secured to any suitable standard 2. Projecting upwardly from the bed-plate are standards 3 which support reels 4 and 5 in place. These reels may be of any suitable construction, though I prefer to have them arranged so that one of the side flanges or spiders of each reel may be 60 removed in order that the coil of the printing plates may be withdrawn or placed upon the supporting spindle. The reel 4 is a supply reel upon which a coil of printing plates may be threaded through the machine and over the segmental guide 6 to the take-off reel 5. The chain of printing plates is made up of individual plates 7 each of which is provided with ears 8 that extend from one edge thereof and which have lateral projections 9 extending therefrom, so that each ear and projections 9 thereof constitute a T-shaped 70 projection. These projections are on one edge of each of the printing plates and are adapted to be seated within the recesses 10 formed in one edge of an adjacent plate. The edge of the printing plate in which the recesses or indentures 10 are formed, is bent or turned 75 over to form open mouth bearings 11 on each side of the depressions 10 which are adapted to receive the projections 9 which extend from the ears of an adjacent plate when the plates are turned to the position represented in Fig. 10 of the drawings. After the projections on the ears have been seated in their bearings in the manner pointed out, the printing plates may be turned from the position represented in Fig. 10, to the 80 position shown in Fig. 9, and it will be understood that the interlocking hinged joints between the printing plates prevent the plates from being separated one 85 from another in every relative position of the plates, except the position indicated in Fig. 10, and this relative position, the plates can never assume in the machine. 90

The printing faces of the plates are preferably formed by striking the printing characters up from the body of the metal plates. It will be understood that by this arrangement the plates can readily be disconnected one from another and the order or arrangement of the printing plates changed at will. The invention, therefore is particularly valuable in preparing mailing lists or the like, wherein changes are being made from time to time. 95

It will be observed that the joints between the hinged 100 printing plates project from only one side of the chain or band, and that the opposite face of the band has a plane continuous surface. The band passes in the direction of the arrow in Fig. 1 from the supply reel to the take-off reel and in so doing the band passes around 105 the impact cylinder drum or platen 12 which has its periphery serrated or grooved at regular intervals as indicated at 13. These serrations or grooves in the

periphery of the platen or drum are spaced apart at distances which correspond to the distances between the hinged joints of the printing plates so that that portion of the drum contained between every two serrations 13, constitutes a bed upon which the rear face of a printing plate is adapted to rest in the movement of the band with the drum. The serrations in the periphery of the drum not only afford means which enable the printing plates to rest flat upon the drum, but they likewise constitute by their engagement with the hinged joints, means for feeding the band forward and maintaining a fixed relation between the surface of the drum and the various printing plates. The band in passing from the supply reel to the drum passes under a freely mounted roller 14 that is carried upon a spindle 15 which projects from an arm 16 that is connected to a threaded stem or laterally projecting pin 17 which extends through fixed standard or support 18 and is engaged on the opposite side of said support 19 by a thumb nut 19. By these means the roller can be adjusted with relation to the face of the impact cylinder or platen 12. In order to accomplish said adjustment it is simply necessary to loosen the thumb nut 19 and raise or lower the roller around the pin 17 until the desired position is attained, when the thumb nut may be tightened and the roller secured in such position. The band after passing around the drum is guided over a roller 20 which is pivoted to a fixed arm 21 which extends laterally from the standard 3. The band next passes over the outer face of the segmental support 6 and from thence to the take-off reel. Motion is transmitted to the various parts of the device through a treadle 21^a which is pivoted at 22 and has a link 23 pivotally connected thereto at 24 intermediate of its ends. The upper end of this link 23 is pivotally secured at 25 to a crank arm 26 that is mounted upon a rock shaft 27. The rock shaft 27 likewise has a crank arm 28 extending therefrom and to the free end of this crank arm is secured one end of a contractile spring 29; the lower end of this spring being secured to a pin 30 which projects laterally to the standard or support of the machine. This spring tends to restore the rock shaft 27, the treadle and other various parts controlled thereby, to the normal position. In addition to the arms 26 and 28 the rock shaft 27 is provided with an upwardly extending arm 31 which is pivoted at 32 to the link 33; the upper end of which is pivotally connected to an arm or link 34 that carries a pawl 35 which engages a ratchet wheel 36. The ratchet wheel 36 is connected to a take-off reel 5 and intermittent rotation is imparted to the reel through the mechanism just described, in order to take up the band of printing plates as they are fed forward by the cylinder 12. The crank arm 26 has a two-part link 37 pivoted thereto at 38^a. This two-part link is provided with right and left hand screw threaded ends 38 with which a turn buckle or capstan screw 39 co-operates in order to shorten or lengthen the link as desired. The upper end of the two-part link 37 is connected at 40 to an oscillating plate 41 which is pivoted upon the shaft or spindle 42 and is provided with a carrier 43 which surrounds the shaft and from which a cam 44 extends. The plate likewise has pivoted thereto at 45 a feed pawl 46 which has connected thereto at 47 a contract-

ile spring 48; the opposite end of the spring being secured to the carrier 43 by a screw 49. The forward face 50 of the feed pawl is straight, whereas the opposite face 51 thereof is slightly rounded at its lower end, so that it may readily ride out of the openings 52 formed 70 between the teeth 53 of the feed wheel 54 during the movement of the pawl with its plate 41 in the direction of the arrow *a* in Fig. 2. The forward flat face 50 of the pawl 46 will on the other hand engage the teeth 53 of the feed wheel 54 and transmit a rotary movement 75 thereto when the feed pawl is moved with its plate in a direction opposite to that indicated by the arrow *a*. The feed wheel 54 which has just been described is operatively connected to the drum or platen 12 so that the intermittent rotary motion imparted to the 80 feed wheel will provide a corresponding movement of the drum. The plate 41 likewise has pivoted thereto at 55, a link 56, the lower end of which is pivoted at 57 to an arm 58 that is fixed to a rock shaft 59 mounted in the portion 60 of the frame of the machine. Extending upwardly from this rock shaft and fixed thereto is a second arm 61 which is pivoted at 62 to a link 63 that has its opposite end pivoted at 64 to a swinging arm 65 that is pivoted upon the shaft or spindle 66 of a ratchet wheel 67. This arm 65 has pivoted thereto 90 at 68 a feed pawl 69 that co-operates with the teeth of the ratchet wheel 67 and these parts are supported upon one side of the ink font 70 and the shaft 66 extends through said ink font and constitutes a shaft for an inking roller 71 that rotates in the ink font and below the level of the ink which is indicated at 72. The inking roller 71 is preferably made of metal, and the periphery thereof bears against a doctor 73 which is secured at its upper end to the interior of the ink font, as indicated at 74 and is in the nature of a metallic 100 plate, such as bronze, that extends from side to side of the ink font, and an adjustment of the free or resilient end of the doctor is afforded by means of set screws 75 which are threaded into openings at the bottom of the ink font, and bear upon the under side of the doctor. Intermediate of the ratchet wheel 67 and the ink font is a gear wheel 76 which is secured to the shaft 66 and meshes with gear wheels 77 and 78. The gear wheel 77 is secured to the shaft 79 that extends through the ink font and has a smooth faced rubber inking roller 80 secured thereto. The gear 78 is secured in a like manner to a shaft 81 which extends through the ink font, and is also provided with a rubber inking roller 82. Both of these rollers 80 and 82 bear upon the types or printing characters on the face of the printing plates as they pass the inking rollers so as to efficiently ink the printing surfaces before they arrive at the printing point. When desired, motion may be transmitted by hand to these rollers through the handle secured to the shaft of the roller 71, though the rollers are automatically rotated during the operation of the machine. Thus,—when motion is transmitted, through the depression of the treadle, to the plate 41 it is effective to move the arm 65 with its feed pawl 69 and when the treadle is released from pressure a forward movement will be transmitted to the pawl 69 by the spring 29 which restores the parts to the normal position. This intermittent rotary movement transmitted to the ratchet wheel is effective to rotate the various inking rollers, and thus constantly provide a 110 115 120 125 130

fresh supply of ink thereto and to ink the printing surfaces of the printing or impression plates. In order to vary the pressure of the inking rollers 80 and 82 in their contact with the printing surface, and in this manner regulate the inking of the printing surfaces, I make the ink font 70 adjustable towards or away from the drum or cylinder 12. This adjustment of the ink font may be accomplished by any suitable means; in the present instance I employ a screw 70^a, which is received within a stud or flange on the supporting plate 70^b and has its inner end extended into a threaded opening in the base of the ink font so that an adjustment of screw 70^a will move the ink font towards or away from the cylinder 12 in accordance with the direction in which said screw is turned. The ink font may be secured in the adjusted position by means of screws 70^c one of which is provided at each side of the ink font and each of these screws passes through a split collar 70^d which bears upon a flange which projects from the side of the font, and when pressure is exerted on the upper faces of these split collars by screwing the screws 70^c into threaded openings in the base 70^b the font may be securely mounted in the adjusted position. It will likewise be observed that by these means I am enabled to remove the ink font entirely in case of necessity.

The feed wheel is firmly locked against rotation by a locking pawl 83 which is pivoted at 84 to a bracket 85 that extends from the frame 60. The nose 86 of the locking pawl is adapted to be seated in the openings 52 in the feed wheel and thus prevent movement thereof in either direction. The locking pawl is forced to the locking position by a spring 87 which has one end secured thereto; the opposite end of said spring being secured to a suitable fixed portion of the machine. A latch 88 is pivoted at 89 to the locking pawl, and when in the position represented in Fig. 2 of the drawings is adapted to bear against a pin or stop 90 which is carried by the locking pawl. The latch is normally held in this position by a contractile spring 91 which is secured at one end to the latch and at its opposite end to the locking pawl. During the movement of the cam 44 in the direction of the arrow *b* this latch will be moved to one side of the cam without raising the nose 86 on the locking pawl out of engagement with the feed wheel; the cam merely vibrating the latch around its pivot 88 and against the tension of its spring 91. When, however, the cam 44 has passed the latch in the manner described and moves in an opposite direction it will cause the locking pawl to be elevated in order to disengage it from the feed wheel 54. The cam 44 is effective to bring about this disengagement at this time because the stop 90 prevents an independent movement of the latch with relation to the locking pawl, and the pressure exerted on the latch is effective to raise the pawl. It will therefore be understood that the vibration of the plate 41 in the direction of the arrow *a* in Fig. 2 will cause the feed pawl 46 to ride free and independently of the feed wheel 54 and the cam 44 will, during this movement, vibrate the latch 88 against the tension of its spring without raising the locking pawl out of engagement with the feed wheel. When, however, the latch 41 is vibrated in the opposite direction the cam 44 which is at this time on the opposite side of the plate 41 from that represented in Fig. 2, will cause the locking

pawl to be raised in order to release the feed wheel, and the feed wheel will be fed forward by the pawl 46 in order to bring a new printing surface to the printing point. Should the operator desire to permanently maintain the locking pawl out of engagement, it is simply necessary to move the slide 95 in the direction of the arrow *c* in Fig. 2, when the cam 96 formed on the slide (see Fig. 6) will be brought into contact with a pin 97 which projects from the rear face of the locking pawl, thus causing the locking pawl to be elevated and maintained out of engagement with the feed wheel. When the slide 95 is moved in an opposite direction the spring 87 of the locking pawl will again force it into engagement with the feed wheel.

The rock shaft 27 which has been described, is provided with a piece or arm 98 which extends therefrom and within a hollow standard or support 99 which constitutes a part of the machine frame. This piece 98 is provided with laterally extending ears 100 and 101; the uppermost ear 100 having a screw threaded aperture 85 for the reception of a set screw 102 and a jam nut 103 maintains it in its adjusted position. The lower stud or ear 101 extends beneath an arm 104 which is loose upon the shaft 27. This arm 104 is formed integrally with an arm or projection 105 which extends into an aperture 106 in a vertical movable bed or carrier 107. The lower face of the arm 105 is adapted to bear upon a rod 108 which is threaded at its lower end as indicated at 109 and is received within a threaded opening in the carrier 107. This rod is preferably made of tool steel 95 and may be adjusted in its bearing in the carrier in order to compensate for wear which takes place by that action of the arm 105 upon the carrier. The head 110 of this rod is adapted to secure a disk or plate 111 to the carrier so as to provide an abutment for the lower end 100 of the spring 112 which is contained within the recess 113 and bears at its upper end against the upper part or wall of the recess. The upper end of this spring bearing as it does against a fixed portion of the machine tends to force the carrier and the parts operatively connected thereto to the lowermost position. The purpose of the piece 98 with the set screws 102 and stud or projection 101 thereon in their co-operation with the arm 104, is to provide means for compensating for articles of different thickness to be printed in the machine. 110 Thus, for instance, if postal cards or the like are to be printed upon, the set screws may be adjusted to the position represented in the drawings, in order to provide for an article of minimum thickness. If, however, magazines or like thick articles are to be printed, the 115 set screw will be raised to the desired height, thus compensating for the additional thickness of the material to be printed. Thus, for instance, if the set screw 102 be elevated, it will permit the carrier 107 to be forced to a lower normal position by its expansion spring 112, and thereby enable the given extent of throw imparted to the carrier to properly print the article carried thereon without danger of injuring the printing surface. The carrier 107 has secured at its upper end a bed 114 which may be adjusted to the desired position thereon by 120 means of the set screws 115 so as to properly present the supporting face thereof in order that an even impression may be provided. It will be understood that the article to be printed rests upon this adjustable bed at the upper end of the carrier and that motion transmit- 125 130

ted to the rock shaft 27 from the treadle will cause the carrier to be elevated, thus bringing the article supported thereon into contact with the printing plate which is in coöperative relation therewith. Extending 5 laterally from the carrier is an arm 116 to which is secured, adjustably or otherwise, one or more studs 117 which support a feed-table 118 in place. It will be observed that this feed-table is at the same height as the upper face of the supporting bed 114 and the table may 10 be provided with one or more suitable guides (not shown) to facilitate the feeding of the sheets or material to the supporting bed on the carrier. By this construction it will be seen that the carrier is provided with an adjustable supporting member whereby the work can 15 be elevated to different positions for the same operation or movement of the carrier, and this without affecting the operation of advancing the drum from the actuating means, which in the present instance is a treadle.

While I have shown and described with considerable 20 particularity one form or embodiment of my invention it should be understood that various changes in the construction may be made without departing from the spirit of my invention.

Having described my invention what I claim and desire 25 to secure by Letters Patent is:

1. In a printing machine, the combination of a revoluble drum having peripheral grooves therein, a chain of hinged printing plates, the hinges of which are received within the grooves of said drum, a reciprocating supporting carrier which is adapted to support and move the material to be printed into contact with a printing surface on said printing plates, means for actuating said carrier, inking rollers, and means for automatically revolving the drum and for moving the inking rollers when the carrier is 35 actuated.

2. In a printing machine, the combination of a revoluble drum having peripheral grooves therein, a chain of hinged printing plates, the hinges of which are adapted to be received within the grooves of said drum, a supply and take-off reel for said chain of printing plates, means for automatically rotating said take-off reel, a reciprocating carrier which is adapted to move the material to be printed into contact with a printing surface on said printing plates, means for actuating said carrier, an ink font, inking rollers which coöperate with the printing surface to supply ink to the latter, and means for automatically revolving the drum and the inking rollers when the carrier is actuated.

3. In a printing machine, the combination of a revoluble 50 drum, a chain of hinged printing plates which coöperate therewith, means for locking said drum against rotation in either direction, an oscillating feeding device for imparting an intermittent rotary movement to said drum, and means for automatically releasing said locking means and maintaining them disengaged during the forward movement of the feeding device and for permitting said locking means to remain in the engaged position during the retractile movement of the feeding device.

4. In a printing machine, the combination of a revoluble 60 drum, a chain of hinged printing plates which coöperate therewith, a locking pawl for locking said drum against rotation, an oscillating feeding pawl for imparting an intermittent rotary movement to said drum, a pivoted latch carried by said locking pawl, a pin with which said latch coöperates and a cam or abutment which coöperates with the latch to automatically raise said locking pawl during the movement of the cam or abutment in one direction, and for permitting said locking pawl to remain in the engaged position during the movement of the cam or abutment in an opposite direction.

5. In a printing machine, the combination of a revoluble 70 drum having peripheral grooves therein, a chain of hinged printing plates which coöperate therewith and the hinges of which are adapted to be seated in said grooves, a lock-

ing pawl for locking the drum against rotation, a locking wheel which coöperates therewith and which is connected to said drum, an oscillating feeding pawl for imparting an intermittent rotary movement to said drum, a pivoted latch carried by said locking pawl, a pin with which said latch coöperates and a cam or abutment which coöperates with the latch to automatically raise said locking pawl through the latch during the movement of the cam or abutment in one direction and for permitting said locking pawl to remain in the engaged position during the movement of the cam or abutment in an opposite direction.

6. In a printing machine, the combination of a revoluble drum, a chain of hinged printing plates which coöperate therewith, means for locking said drum against rotation, an oscillating feeding device for imparting an intermittent rotary movement to said drum, and means for automatically releasing said locking means during the movement of the feeding device in one direction and for permitting said locking means to remain in the engaged position during the movement of the feeding device in an opposite direction, a pin on the locking pawl and a hand operated cam which is adapted to contact with said pin to raise and maintain the locking pawl out of engagement.

7. In a printing machine, the combination of a chain of printing plates, a drum coöperating therewith, a carrier for the material or article to be printed, an actuating device operatively connected to feed the printing plates, to turn the drum, and to reciprocate the carrier, and means for adjusting said carrier without affecting the feed of the printing plates or the operation of the drum, whereby different thicknesses of material to be printed may be compensated for.

8. In a printing machine the combination of printing instrumentalities, a carrier for the material to be printed, a rock shaft 27, means for rocking said shaft, an arm secured to said shaft, a set screw carried by the arm and means with which the set screw contacts and which coöperates with the carrier to move it.

9. In a printing machine the combination of an impact drum, a chain of printing plates coöperating therewith, a carrier for the material to be printed, a rock shaft 27, a treadle for rocking said shaft, an arm secured to said shaft, laterally extending studs projecting from said arm, a set screw carried by one of said studs, a loosely disposed arm which extends between said studs and with which the set screw contacts and operative connections between the loosely disposed arm and the carrier.

10. In a printing machine, the combination of a printing band, a drum arranged to support the band to bring successive portions to a printing position, a carrier for holding the work, an actuating device arranged to advance the drum and also to operate the carrier to and from the printing position, and adjustable means on said carrier for varying the position to which the work is carried at each operation thereof.

11. In a printing machine, the combination with a band of jointed printing plates, of a drum rotatably supported and arranged to engage the plates successively on rotation, a carrier movable to and from the drum, means for moving the drum, means connected with said means for reciprocating the carrier at each advance of the drum, and an engaging member on the carrier adjustable thereon to vary the position to which the work is carried at each reciprocation of the carrier.

12. In a printing machine, the combination with a band of jointed printing plates, of a drum rotatably supported and arranged to engage the plates successively on rotation, a carrier movable to and from the drum, means for moving the drum, means connected with said means for reciprocating the carrier at each advance of the drum, an engaging member on the carrier adjustable thereon to vary the position to which the work is carried at each reciprocation of the carrier, and means for adjusting the member on the carrier.

In testimony whereof we have hereunto signed the foregoing specification this 13 day of Feby. 1902.

GEORGE F. HOPKINS.
